UNITED STATES PATENT OFFICE.

JAMES B. CASTLE, OF SAN FRANCISCO, CALIFORNIA, ASSIGNOR OF ONE-HALF TO
ROBERT S. MOORE, OF SAN FRANCISCO, CALIFORNIA.

CRANKING MECHANISM FOR AUTOMOBILES.

974,235.

Specification of Letters Patent.

Patented Nov. 1, 1910.

Application filed September 7, 1909. Serial No. 516,322.

To all whom it may concern:

Be it known that I, JAMES B. CASTLE, a citizen of the United States, residing in the city and county of San Francisco and State of California, have invented certain new and useful Improvements in Cranking Mechanism for Automobiles, of which the following is a specification.

The hereinafter described invention relates to means for automatically disconnecting the cranking means of a gasoline car, on a back explosion or firing of the engine occurring during the cranking operation.

To comprehend the invention reference 15 should be had to the accompanying sheet of drawings, wherein—

Figure 1 is a longitudinal sectional view of the casing or shell within which the operating mechanism is located, the crank or cranking shaft being illustrated in clutch with the shaft of the engine to be cranked. Fig. 2 is a front view of the casing or shell with its cap or cover plate removed to disclose the arrangement of the drive mechanism for the crank shaft and the means for automatically disconnecting the same on a back explosion of the engine being cranked.

In the drawings, the numeral 1 is used to designate any suitable form of an outer shell 30 or casing designed to be secured preferably to the front of an ordinary automobile, and 2 the crank or cranking shaft slidably held therein for rotation. This shaft carries a clutch member 3 for engagement with the 35 clutch member 4 on the free end of the engine shaft 5.

The forward end portion of the crank or cranking shaft 2 is feathered to and extends through the circular head 6, rotatably held 40 within the casing or shell 1, the projecting end of the said shaft extending within a circular socket 7 formed in the hub 8, located in the said casing or shell 1. This hub 8 is formed with a projecting disk 9, of a diameter 45 slightly greater than that of the head 6, and to the said disk is pivoted, by means of the pin 10, a dog 11, the hooked end of which engages with a notch 12 in the face of the head 6 and holds the same locked to the drive disk 9.

To the hub 8 is feathered a short stud 13, which projects beyond the cap or cover plate 14 of the casing or shell 1, and its outer end is shaped to receive a cranking handle 15.

Within the casing or shell 1 is formed a

rack ring 16, with which engages a pawl 17, pivoted to the head of the dog 11 and held into engagement with the teeth of the immovable rack ring 16 by the spring 18, the pressure of which also serves to maintain 60 the dog 11 in locked engagement with the head 6.

In the operation of cranking the engine for the starting of a car, the parts being positioned as illustrated in the drawings, the 65 operator turns the cranking handle 15 for rotating the hub 8, the rotation of which is imparted to the head 6, through the medium of the locked engagement of its drive disk 9 therewith, which head in turn transmits its 70 rotary motion to the crank or cranking shaft 2, for rotating the engine shaft 5 to crank the engine. In case of a back fire or explosion of the engine occurring, a violent reverse rotation is transmitted to the crank or 75 cranking shaft 2, which, ordinarily would suddenly throw the handle 15 to the injury of the operator. The back throw thus occasioned is taken care of and the drive means automatically released in the present device 80 as follows:—The reverse throw of the cranking shaft is transmitted through the connected parts to the drive disk 9, and the strains placed thereon tend to rotate the same in an opposite direction to its movement during the cranking of the engine. This pulling strain is resisted by the pawl 17, which locks with the immovable rack ring 16 on such "back lash" of the operating mechanism, with the result that the 90 pawl serves as a lever to inwardly swing the head of the dog 11 and release the same from locked engagement with the head 6, thus automatically releasing the drive mechanism from the crank or cranking shaft 2. 95 and removing the "back kick" of the said shaft from the crank handle 15.

By reason of the limited slide movement permitted the crank or cranking shaft within the socket 7 of the hub 8, the same will 100 give forwardly under the rotation of the engine shaft 5, when the engine has been cranked, so as to place its clutch member 3 out of engagement with the clutch member 4 of the engine shaft 5, as usual in this class 105 of devices.

The hub 8, disk 9 and dog 11 constitute the drive mechanism for imparting rotation to the crank and cranking shaft 2, while the pawl 17 and immovable rack ring 16 serve as 110

the clutch means for automatically disconnecting or releasing the drive mechanism from locked engagement with the head of the crank or cranking shaft 2 on a back explosion of the engine being cranked.

Having thus described the invention what is claimed as new and desired to be protected by Letters Patent is—

The combination with a casing for attachment to an automobile, of a cranking shaft extended therein, said shaft carrying a clutch member for engagement with the clutch member of an engine shaft, a head rotatable within the casing and through which the cranking shaft is slidale, a hub into which the projecting end of said shaft extends, a disk carried by said hub, a dog

pivoted to said disk for engagement with the head for the cranking shaft, a rack ring immoveable in the casing, a pawl pivoted to the head of the dog for engagement with the said ring to release the dog from engagement with the head of the cranking shaft on a back explosion of the engine being cranked, and devices for imparting rotation to the hub within the casing to operate the cranking shaft.

In testimony whereof I have signed my name to this specification in the presence of two subscribing witnesses.

JAMES B. CASTLE.
